UNITED STATES PATENT OFFICE.

THOMAS E. JONES, OF GUINEA, VIRGINIA.

FENCE-POST.

No. 841,532.

Specification of Letters Patent

Patented Jan. 15, 1907.

Application filed January 23, 1906. Serial No. 297,496.

To all whom it may concern:

Be it known that I, THOMAS E. JONES, a citizen of the United States, residing at Guinea, in the county of Caroline and State 5 of Virginia, have invented new and useful Improvements in Fence-Posts, of which the following is a specification.

This invention relates to fence-posts, the object of the invention being to provide composite posts for the purpose specified which will combine strength and durability and which may be manufactured rapidly and economically, the complete post being practically indestructible and forming a most effective and satisfactory support for a fence of any description.

With the above and other objects in view, the nature of which will more fully appear as the description proceeds, the invention consists 20 in the novel construction, combination, and arrangement of parts hereinafter fully described, illustrated, and claimed.

In the accompanying drawings, Figure 1 is a perspective view of a fence-post constructed in accordance with the present invention. Fig. 2 is a central vertical section through the same. Fig. 3 is a cross-section taken in line with one of the fence-wires. Fig. 4 is a detail section through the lower portion of the 30 post, showing a slight modification in the means for anchoring the post to its supporting-base. Fig. 5 illustrates another form of the internally-threaded member.

Like reference-numerals designate corresponding parts in all the figures of the drawings.

The post contemplated in this invention under the preferred embodiment thereof comprises an outer jacket or casing 1, which may 40 be either square or round or of any other desired form in cross-section, a square jacket being shown in the drawings for the purpose of disclosing the nature of the invention. This outer jacket or casing may be of any desired material, such as wood or metal, the latter being preferred on account of its lasting qualities.

Fitted to the top of the post and supported on the upper end of the jacket 1 is a cap or 50 watershed 2, preferably pyramidal in shape and either solid or hollow in cross-section, said cap being provided with a central vertical opening 3, through which passes a center bolt 4, by means of which the post proper is 55 anchored to the base.

The center bolt 4 under the preferred embodiment of the invention comprises an eye 5 at its upper extremity, which projects above the cap 2. Said bolt 4 passes vertically entirely through the post proper and has its 60 lower end inserted in a base 6, consisting of a block of concrete or cement of any suitable depth, said base being nearly or quite embedded in the ground and the upper end of said base being square or flat in order that 65 the bottom of the post proper may rest squarely thereon, as shown in the drawings. The lower end of the center bolt 4 may either be enlarged and threaded, as shown at 7 in Fig. 2, to form an anchor which engages the 70 base, or a nut-holding cup 8 may be inserted or molded in the base 6, as shown in Fig. 4, to receive an internally-threaded member or nut 9, into which the threaded lower end of the center bolt 4 passes. The arrangement 75 shown in Fig. 4 is ordinarily preferred for the reason that it enables the center bolt to be turned by placing a bar or lever through the eye 5 and sweeping said bar through a circle, thus drawing the post proper downward 80 firmly against the base.

The outer jacket or casing 1 is filled with concrete or cement, as shown at 10, and such filling may extend from the base upward entirely to the cap 2 or at any desired distance 85 within the casing. Holes 11 are formed horizontally through the post to receive the fence-wires 12, and the keyholes 13 are formed at various points in the casing to receive portions of the filling 10 of the jacket which 90 protrude into the holes 13 and form keys which securely anchor the filling and casing or jacket together.

In some cases the outer jacket or casing 1 may be dispensed with after the concrete 95 body portion 10 of the post is formed and hardened; but ordinarily the said outer casing or jacket will be retained, as it adds to the strength, durability, and appearance of the post. Where such outer jacket or casing is 100 dispensed with, the post should be painted or provided with some suitable protecting-coating.

Another plan is shown in Fig. 5, in which the internally-threaded member consists of a 105 section of pipe 19, embedded in the base 6 of the post to receive the correspondingly-threaded lower end of a bolt, rod, or pipe 20, which passes upward partially or wholly through the main body of the post. 110

Having described the invention, I claim—

1. A post embodying a concrete base, a metallic casing mounted on the base, a filling in said casing, a pyramidal cap on the upper end of the post, and a center bolt passing downward through the cap and filling and having its lower end anchored in the base.
2. A fence-post comprising a concrete base, a metallic casing mounted thereon a filling in said casing, a cap surmounting the post, and an eyebolt passing downward through the cap and the post proper and anchored in the base.
3. A post comprising a concrete base, a metallic casing mounted on said base a filling in said casing, a cap surmounting the post, a threaded bolt passing downward through the cap and post and entering the base, and means within the base for engaging the threaded portion of said eyebolt.
4. A post comprising a concrete base, a metallic casing mounted on said base a filling in said casing, a cap surmounting the post, a bolt passing downward through the cap and post and entering the base, a nut-holding cup

in the base and an internally-threaded member within said cup engaging the threaded lower end of the eyebolt.

5. A post comprising a concrete base, a metallic post, jacket or casing mounted on said base, a concrete filling in said jacket, a cap surmounting the post, and a center bolt passing downward through the cap and filling of the post and having its lower end threaded and held in the base.

6. A post comprising a concrete base, a metallic jacket or casing mounted thereon and provided with keyholes, a concrete filling in said post having keys which enter said holes in the casing, a cap surmounting the post, and a center bolt passing downward through the cap and post and entering the base.

In testimony whereof I affix my signature in presence of two witnesses.

THOMAS E. JONES.
